(57) **CLAIM**

The ornamental design for a wearable device, as shown and described.

DESCRIPTION

FIG. 1 is a top perspective view of a wearable device in an assembled state;

FIG. 2 is a top perspective view of the wearable device in a disassembled state;

FIG. 3 is a top perspective view of the wearable device in a disassembled state, with a watch body thereof rotated relative to a holder thereof to illustrate how assembly and disassembly thereof may be accomplished by a user twisting the watch body relative to the holder;

FIG. 4 is a bottom perspective view of the wearable device in a disassembled state;

FIG. 5 is a front side view of the wearable device in a disassembled state;

FIG. 6 is a rear view of the wearable device in a disassembled state;

FIG. 7 is a top view of the wearable device in a disassembled state;

FIG. 8 is a bottom view of the wearable device in a disassembled state;

FIG. 9 is a left side view of the wearable device in a disassembled state; and,

FIG. 10 is a right side view of the wearable device in a disassembled state.

The broken lines shown in the figures illustrate portions of the display device that form no part of the claimed design. The oblique shade lines in the figures show a transparent, reflective, or shiny surface, and not surface ornamentation.
